OARLOCK

Ernest J. Slizewski, Eagle River, Wis., assignor to
John D. Gilligan, Rhinelander, Wis.

Application September 7, 1944, Serial No. 553,064

7 Claims.

(Cl. 9—26)

This invention relates to oarlocks or rowlocks, and more particularly to oarlocks of the North River type, which are secured to the loom.

Oarlocks, which are secured to the loom of the oar, are usually connected by boring a suitable hole through the loom, into which the oarlock pin is inserted. This tends to weaken the oar and, if the hole is not bored true, another hole must be provided, which causes further weakness. Since such oarlocks are intended to be permanently fixed to the oar, if the oarsman desires to increase or decrease the length of oar from the spoon end to the oarlock, the change must be made at the expense of causing increased weakness in the oar, as is apparent.

An important object of the invention is to provide a novel oarlock which requires no holes, sockets or the like to be provided in the oar and the oarlock may be permanently or detachably secured to the oar.

Another important object is to provide such an oarlock, which may be readily secured to looms of different diameters. Such diameters vary with the weight and kind of wood of the oar, such as looms of $1\frac{3}{4}$ inches, $1\frac{1}{8}$ inches and 2 inches.

Still another important object is to provide an oarlock adapted to be disposed at any desired distance from the spoon end and which will remain in such position until readily moved along the length of the loom to another fixed position.

A major object is to provide a detachable oarlock, consisting of only six parts and including a single means for adjustably and firmly clamping the oarlock to the loom.

Another major object is to provide a clamping means for a removable oarlock, which means includes a single bolt and a thumb-nut, disposed out of the way, the position of the thumb-nut being such that it is substantially recessed, so that lines and the like will not be caught and tangled by it.

Yet another important object is to provide a detachable oarlock which is relatively inexpensive to manufacture since the major portions may be stamped from suitable metal and readily formed to the desired contours.

A very important object is to provide a detachable oarlock depending upon clamping means, which will not be subject to excessive wear since it comprises but few parts and the metal surfaces of moving parts in contact with each other are limited and can be said to represent only little more than line contact.

Another object is to provide oarlocks which

may be folded so as to decrease size, for economy, in transportation, storage and the like.

Other objects and advantages of the invention will be apparent during the course of the following detailed description of the invention, taken in connection with the accompanying drawings, forming a part of this specification, and in which drawings:

Figure 1 is a partial elevation and partial vertical cross section of the novel oarlock.

Figure 2 is a side elevation thereof.

Figure 3 is an elevation of one of a pair of clamping members forming a part of the new oarlock.

Figure 4 is a fragmentary elevation of the upper portion of the shank of the oarlock.

Figures 5 to 7 inclusive are views illustrating attachment of the oarlock to oars of various sized looms.

In the drawings, wherein for the purpose of illustration is shown a preferred embodiment of the invention and wherein similar reference characters designate corresponding parts throughout the several views, the letter A designates the novel oarlock, and the letters B, C and D, oars, having looms of different circumferences.

The novel oarlock includes a support 10, loom-engaging jaws 11, means 12 providing a pivotal and rocking connection between the jaws 11 and the support 10, and adjustable coupling means 13 for permitting moving of the jaws toward and away from each other and securing them in a clamping position about the loom of an oar.

In the example shown, the support 10 comprises a cylindrical shank 15 and a head 16, the latter being wider than the shank's diameter, and this head may be polygonal having opposite, substantially vertical side faces 17, and opposite substantially vertical end faces 18. Through the head

16 from the faces 17 extends a substantially horizontal pin-accommodating bore 19. There may be a suitable vertical perforation 20 from the upper face 21 of the head 16 to the bore 19 for the passage of oil or the like to the bore. Of course, the shank 15 is adapted to extend vertically into a socket or the like in the gunwale of the boat, as is well known in the art, and the head 16 projects above the gunwale.

There are two, like, loom-engaging jaws 11, each formed of a thin sheet of suitable metal, and each including an upper loom-engaging portion 25, lower head-engaging portion 26 and intermediate portion 27. The loom-engaging portion 25 of each jaw is arcuate or outwardly bowed as at 28, to conform somewhat to the circumference

of the loom of an oar. However, the contours of this novel detachable oarlock is such that the jaws may grasp and securely hold looms of various circumferences. It will be seen in Figure 1, particularly, but also in Figures 5 to 7 inclusive, that the vertical plane of the outermost portion of the outer face 28 of the loom engaging portion extends outwardly beyond any other portion of the oarlock. This feature is important, as will be subsequently explained.

As for the lower head-engaging portion 26 of the jaw 11, this is also arcuate, but inwardly bowed as at 30. This contour of the jaw is also important. Extending through this inwardly-bowed portion 26 is a pin-accommodating perforation 31 which is oval, with the largest diameter extending longitudinally of the jaw, as may be seen in Figure 3. Preferably, the center of the perforation 31 is at the crest of the bow.

The intermediate portion 27 of the jaw 11 may be slightly arcuate as at 32 and is provided with a bolt-accommodating perforation 33 which may also be oval, and disposed with its longest diameter longitudinally of the jaw 11. Surrounding the perforation 33 is a lock washer-accommodating depression 34 in the outer face of the jaw, as shown in Figure 3.

The means 12 providing a pivotal and rocking connection between the jaws 11 and support 10 comprises a pin 35 extending loosely through the bore 19, this pin 35 having reduced, cylindrical, projecting ends 36, so that shoulders 37 are provided at the juncture of the ends 36 and intermediate portion 38 of the pins 35 within the bore 19. These projecting ends 36 support the jaws 11, one jaw on each projecting end, by extending through the perforations 31 and outwardly of them. It should be noted that the smallest diameters of the perforations 31 are only slightly larger than the diameters of the ends 36 and less than the diameter of the intermediate portion 38 of the pin 35, so that the jaws retain the pin from dropping out, since the shoulders 37 contact, but only slightly more than line contact, the inner faces of the jaws at the bowed portion 26. This construction of bowed portions 26, oval perforations 31, pin ends 36 and substantially vertical faces 17 contacting the bowed portions 26 in little more than mere line contact, permits both pivoting and rocking of the jaws 11, as is now apparent. Pivoting permits the jaws to move with the loom upon dipping the oars and rocking permits the oarlocks to be attached to looms of various diameters, as in Figures 5 to 7 inclusive. Of course, this last is partly dependent upon the oval-shaped perforations 33 of the intermediate portions 27 of the jaws 11, as will be next explained.

Adjustable coupling means 13 for permitting other movements of the jaws and securing them in clamping positions about looms, may be a simple bolt 40, with shank 41, head 42, and, preferably, a thumb-nut 43. The shank 41 extends through the oval-shaped perforations 33 with the head 42 bearing against one outer face of one jaw 11 and the thumb-nut 43 bearing against the outer face of the other jaw. Tightening of the thumb-nut will cause the jaws to rock toward each other and loosening the thumb-nut 43 will cause them to rock away from each other, because of the position of the rocking surface and outward projection of the upper loom-engaging portion 25 of the jaws which is the heavier and largest portion of the jaw structure. Accommodated in the depression 34 surrounding the perforation 33 may be a lock washer, or the like.

Because of the limited contact of moving parts there is little wear and noise.

Due to the outward projection of the upper loom-engaging portion 25 of the jaws 11 and the position of the thumb-nut 43 and head 42 of bolt 40 with respect to this outward projection, the thumb-nut is substantially recessed and shielded by the outward projection of the jaws, as is apparent in Figures 1 and 5 to 7 inclusive, the wings are not apt to be accidentally struck and the nut loosened nor are fishing lines, etc., apt to become caught thereon.

Oil, may be introduced into the vertical perforation 29 in the head 16 to lubricate any and all the surfaces of the oarlock, which normally contact each other during the rowing movement of the oarlock.

Various changes may be made to the form of invention herein shown and described without departing from the spirit of the invention or scope of the claims.

I claim:

1. In a detachable oarlock, a support including a head; a pair of jaws, each including a loom-engaging portion; means pivotally connecting said jaws to said head; and means to adjustably secure said jaws to a loom, said last-named means being disposed above said first-named means, below said loom-engaging portions and wholly inwardly of the vertical planes of the outermost longitudinal faces of said portions.

2. In a detachable oarlock, a support including a head; a pair of jaws, each including a loom-engaging portion; means pivotally connecting said jaws to said head; and nut and bolt means to adjustably secure said jaws to a loom, said last-named means being disposed above said first-named means, below said loom-engaging portions and wholly inwardly of the vertical planes of the outermost longitudinal faces of said portions.

3. In an oarlock, a support, including a head provided with a substantially horizontally-disposed bore; a pin extending loosely through said bore and projecting outwardly of each end thereof; a pair of jaws having arcuate, loom-engaging portions at their upper end sections, arcuate portions at their lower end sections rockably engaging said head, and an oval perforation in each of the last named arcuate portions, with the projecting ends of said pin extending through said perforations; and means to rock said jaws upon said head, so as to move said loom-engaging portions toward and away from each other.

4. In an oarlock, a support, including a head provided with a substantially horizontally-disposed bore; a pin extending loosely through said bore and projecting outwardly of each end thereof; a pair of jaws having arcuate, loom-engaging portions at their upper end sections, arcuate portions at their lower end sections rockably engaging said head, and an oval perforation in each of the last named arcuate portions, with the projecting ends of said pin extending through said perforations; and means to rock said jaws upon said head, so as to move said loom-engaging portions towards and away from each other, said means being disposed above said head and below said loom-engaging portions of said jaws.

5. In an oarlock, a support including a head having a pair of substantially flat, opposite, vertical faces and a horizontal bore extending from one of said faces to the other face; a pin loosely extending through and projecting outwardly of each end of said bore; a pair of jaws, one carried by one projecting end of said pin and the

other carried by the other projecting end of said pin, each jaw having an upper loom-engaging portion and a lower bowed portion with substantially the center of the bow of said bowed portion being in contact with said face at the area of said face adjacent said bore; and means to rock said jaws, upon the bowed portions thereof, over said faces, so as to move said loom-engaging portions toward and away from each other.

6. In an oarlock, a support including a head having a pair of substantially flat, opposite, vertical faces and a horizontal bore extending from one of said faces to the other face; a pin loosely extending through and projecting outwardly of each end of said bore, the projecting ends of said pin being of reduced diameter; a pair of jaws, one carried by the projecting end of said pin and the other carried by the other projecting end of said pin, each having an upper loom-engaging portion and a lower bowed portion, provided with an oval perforation accommodat-

ing said projecting ends of said pins, the smallest diameter of said perforations being less than the diameter of the intermediate portion of said pin, with substantially the center of the bow of said bowed portion being in contact with said face at the area of said face adjacent said bore; and means to rock said jaws, upon the bowed portions thereof, over said faces, so as to move said loom-engaging portions toward and away from each other.

7. In a foldable, detachable oarlock, a support including a shank and a head, with said head greater in width than the diameter of said shank, a pair of loom-engaging jaws; means securing said jaws to said head at opposite sides thereof, for pivoting and rocking of said jaws, each of said jaws having a perforation intermediate its ends; a bolt extending loosely through said perforations and projecting from one of them; and a nut for said bolt.
